DRYING CHAMBER

William Spencer Bowen, Westfield, N. J.

Application June 1, 1938, Serial No. 211,119

13 Claims. (Cl. 34—34)

This invention relates to drying chambers, and more specifically to a drying chamber for removing the entrained moisture from suspended solids which have been reduced to a finely divided state.

In removing solids from the liquid in which they are suspended, spray drying processes are generally used in which the fluid suspensions are atomized and heated air is passed through the particles while they are in a finely divided state, so that the suspended liquid may be readily evaporated and the solid material obtained in the form of a fine powder.

In certain of these processes the fluid suspension is sprayed in at the top of a drying chamber and a whirling column of air is directed through it which mixes with the finely divided suspended material to form a vortex which moves downwardly in a helical path. It has been found, however, that the vortex tends to spread out as it moves downwardly in the drying chamber and some of the suspended material is thrown off on the wall of the drying chamber before the moisture has been completely removed, thus forming an undesirable layer of solid material on the surfaces of the drying chamber. The spreading out of the vortex furthermore, gives rise to numerous dead spaces within the chamber in which the dried material is able to collect.

An attempt has been made in other constructions to confine the vortex to the central portion of the drying chamber by feeding in the air tangentially. When thus fed, however, the air forms a spirally rotating column which, although it prevents the finely divided fluid from being thrown off on the surfaces of the drying chamber, does not mingle with the fluid to any great extent so that disproportionately large quantities of air are required to obtain a product having the desired dryness.

An object of the invention accordingly, is to provide a drying chamber for rapidly and effectively reducing the moisture content of atomized solids, in which the finely divided material is confined centrally in the chamber for its entire length.

A further object of the invention is to provide a drying chamber of the above character from which the dried solids may be removed without substantially disturbing the vortex in the central portion thereof.

Another object of the invention is to provide a drying chamber of the above character having an exhaust outlet of small dimensions for removing the dried solid without breaking up the vortex.

In a preferred embodiment of the invention, atomized fluid is fed in at the top of the drying chamber and a spirally rotating column of heated air is fed downwardly through the atomized fluid forming a vortex in which the air is thoroughly mixed with the fluid particles. Heated air is then fed in about the periphery of the drying chamber in such fashion that it has both radial and tangential components, so that while it is directed neither radially nor tangentially into the vortex, the incoming air gets a circulatory motion and, at the same time, penetrates to the center of the chamber. The movement of the vortex gives it an additional component so that it tends to move downwardly and the moisture laden particles are continually maintained in contact with heated air. The radial component of the incoming heated air tends to confine the vortex and prevent it from spreading out, so that it is kept centrally in the drying chamber. Thus the sprayed material is kept away from the walls of the drying chamber and is maintained in suspension until substantially all of the moisture has been removed.

Cold air is fed into the lower portion of the drying chamber in the same manner as described above for the heated air, and it serves to bring the temperature of the product down to the point where it may be conveniently exhausted. The incoming cold air also has a radial component which aids in concentrating the vortex in the central portion of the drying chamber so that there are no dead spaces within which the dried product may collect.

When the material has been completely dried, it is exhausted through a cone-shaped outlet which tends to maintain the vortex in the central portion of the chamber. This outlet preferably is surrounded by a scroll-shaped elbow which directs the air-suspended dried product to an outlet duct without disturbing the whirling motion of the vortex to any appreciable extent. The scroll elbow obviously occupies only a small amount of space, which is of great advantage where only a limited space is available. If there is sufficient space, however, an elongated funnel-shaped outlet may be used which will also maintain the flow of air in the vortex up to the point where the material is exhausted from the apparatus.

This invention, therefore, provides a drying chamber in which the sweeping action of the vortex throughout all portions of the chamber rapidly and effectively removes moisture from the suspended solids while keeping them away

from its walls. It further provides an improved exhaust outlet construction, by means of which all of the dried material may be removed from the chamber without impairing the motion of the vortex in any way.

Additional objects will be apparent from the following detailed description taken in connection with the accompanying drawing in which:

Figure 1 is a view in elevation showing a drying chamber constructed in accordance with this invention;

Figure 2 is a view in plan illustrating the form of the scroll-shaped inlets;

Figure 3 is a bottom view of the drying chamber shown in Figure 1;

Figure 4 is a view in section taken through the line 4-4 on Figure 2 and looking in the direction of the arrows;

Figure 5 is a partial view in elevation showing a modified form of outlet for exhausting the dried material without disturbing the vortex in the chamber.

In the embodiment shown in Figure 1, the drying chamber is formed in three sections, 10, 11 and 12, which are secured coaxially to one another by suitable flanges and bolts. The section 10 is cylindrical in shape and is surrounded by a scroll casing 13 which is provided with an inlet 14 through which heated air may be supplied to the chamber. About the periphery of the section 10, a tapered slot 15 is formed through which the heated air is adapted to be uniformly admitted to the drying chamber from the scroll casing 13. The narrow portion of the slot is formed near the portion of the scroll casing 13 which has the greatest radius, and the slot diverges substantially linearly so that its widest portion is adjacent the part of the scroll casing of least radius. With this construction, the air inlet area is small where the pressure is high, and is large where the pressure is low, so that air is admitted substantially uniformly about the periphery of the section 10.

On the upper surface of the section 10, a scroll casing 16 is formed in which the atomizer 17 is adapted to be secured and to which heated air is supplied from the inlet duct 20. The atomizer 17 extends downwardly into a converging passage 18 which terminates in an annular outlet 19 from which heated air may be directed downwardly through the atomized fluid. It will be noted that the passage of air through the outlet 19 from the scroll casing 16 provides a spirally rotating downwardly moving column of air which is directed through the finely divided fluid. The fluid is carried downwardly along with the heated air, thus forming a vortex of rapidly moving air and solid particles.

The air directed into the chamber through the tapered slot 15 has a radial component which tends to prevent the central vortex from spreading to the walls of the chamber and, at the same time, it has a tangential component so that it continues to move in a spiral path within the chamber. Thus the vortex comprising a mixture of heated air and suspended particles is almost exclusively confined in the central portion of the drying chamber, so that the moisture-laden solid particles are prevented from being thrown off on its surfaces.

The second section 11 which is mounted coaxially with the section 10 is provided with a similar scroll casing 21 to which cold air is supplied through an inlet 22. A tapered slot 23 is formed in the periphery of the section 11, its narrowest

portion being adjacent the portion of the scroll casing of greatest radius, and its widest portion being adjacent the portion of the scroll casing of least radius. As pointed out above in connection with the slot 15, this tapered slot allows the cold air to enter the drying chamber substantially uniformly about its periphery, and as before, the incoming air has both radial and tangential components, so that the cold air also aids in confining the vortex to the central portion of the drying chamber. The cold air serves to remove heat from the substantially dry particles to reduce their temperature sufficiently so that they may be handled after being exhausted from the drying chamber.

The third section 12 comprises a short cone-shaped member secured coaxially to the section 11 and surrounded by a scroll casing 24, which is provided with an outlet 25 from which the dry air-suspended product may be exhausted. In the bottom of the scroll casing 24 a cone-shaped member 26 is formed whose vortex extends substantially into, and centrally of, an outlet opening 27 formed in the bottom of the cone 12. The conical shape of the section 12 maintains the vortex in the central portion of the drying chamber and, at the same time, directs it to the scroll casing 24 so that the dried material can be readily exhausted without disturbing the air flow in the vortex by any substantial amount.

The same result may be secured by the modification shown in Figure 5, in which a member 28 is secured to the section 11, which forms a downwardly extending passage converging to an elbow portion 29, from which the dried material may be exhausted through an outlet 30. This construction also enables the dried material to be exhausted from the chamber without breaking up the vortex, although it increases the height of the drying chamber to some extent.

The invention provides an improved drying chamber in which the atomized solids are mixed with heated air in a vortex which is confined to the central portion of the chamber, thus preventing the solid particles from being thrown off against the walls of the chamber before the moisture has been completely removed from them, and preventing the collection of dried material in dead spaces within the chamber. It furthermore provides an improved exhaust construction by means of which the dried solids may be readily and effectively removed from the drying chamber without breaking up the fluid flow in the vortex.

It will be evident that numerous changes in form and detail are possible within the scope of the invention and although a specific embodiment has been described above, it is not intended to be limited in any way thereby, except as defined in the following claims.

I claim:

1. A drying apparatus for removing moisture from atomized particles comprising a chamber having a slot therein, means to introduce atomized fluid to the chamber, means forming an opening in the chamber for directing an axially moving and rotating column of air over the moisture-laden particles to form a vortex, and a scroll casing on the chamber cooperating with the said slot for directing air into the chamber inwardly and off a tangent of the periphery of the chamber, for confining the vortex centrally therein and spaced from the chamber walls.

2. A drying apparatus for removing moisture from atomized particles comprising a chamber having a tapered slot therein, means to introduce

fluid to the chamber, means forming an opening in the chamber for directing an axially moving and rotating column of air over the moisture-laden particles to form a vortex, and a scroll casing on the chamber over the slot, the narrow portion of the slot being adjacent the portion of the scroll casing of greatest radius, and the wide portion of the slot being adjacent the portion of the scroll casing of least radius, for directing air uniformly into the said chamber to confine the vortex centrally therein and to space it from the chamber walls.

3. A drying apparatus for removing moisture from atomized particles, comprising a chamber, means to introduce atomized fluid to the chamber, means forming an opening in the chamber for directing an axially moving column of air over the moisture-laden particles for forming a vortex, means in the chamber forming an inlet for directing air thereto, inwardly and off a tangent of the periphery of the chamber, for confining the vortex centrally within the said chamber, means in the bottom of the chamber forming a converging outlet, and a scroll casing over the outlet for exhausting the dried particles without substantially disturbing the vortex in the chamber.

4. In a drying apparatus for removing moisture from atomized particles, the combination of a casing, means in the casing forming a tapered slot extending substantially around the periphery thereof, and means for introducing air inwardly and off a tangent of the periphery of the casing through the slot into the casing.

35 5. In a drying apparatus for removing moisture from atomized particles, the combination of a casing, means in the casing forming a tapered slot therein extending substantially around the periphery thereof, and a scroll casing over the slot for introducing air inwardly and off a tangent of the periphery of the casing into the casing.

45 6. In a drying apparatus for removing moisture from atomized particles, the combination of a casing, and a scroll casing over the slot, the narrow portion of the slot being adjacent the portion of the scroll casing of greatest radius, and the wide portion of the slot being adjacent the portion of the scroll casing of least radius.

50 7. In a drying apparatus for removing moisture from atomized particles, the combination of a casing having a lower portion converging to an outlet, means to supply air to the casing to form a vortex, and scroll means cooperating with and coaxial to the said outlet for exhausting the air and dried material outwardly from the casing without substantially disturbing the vortex therein.

8. In a drying apparatus for removing moisture from atomized particles, the combination of a casing having a lower portion converging to an outlet, means to supply air to the casing to form a vortex, a scroll casing on the casing over the outlet, and a deflecting surface in the bottom of the said scroll casing, converging upwardly into, and centrally of the said outlet, for exhausting the dried material from the casing without substantially disturbing the vortex therein.

9. A drying apparatus for removing moisture from atomized particles, comprising a casing having an opening in the top thereof, means in the opening to introduce atomized fluid into the cas-

ing, means to supply a rotating column of heated air to the said opening in the direction of flow of the atomized fluid to form a vortex in the casing, means in the casing forming a slot therein, means to supply heated air inwardly and off a tangent of the periphery of the casing through the slot into the casing, means forming a second slot in the casing, means to supply cold air inwardly and off a tangent of the periphery of the casing through the said second slot into the said casing, and means in the lower portion of the casing forming a passage converging to an outlet for exhausting dried material without substantially disturbing the vortex, whereby the vortex may be maintained centrally in the casing, and spaced from the casing walls, throughout its entire length.

10. A drying apparatus for removing moisture from atomized particles, comprising a casing, a cover on the casing having a downwardly converging opening therein, a scroll casing over the opening, an atomizer in the scroll casing extending into and centrally of the said opening forming an annular inlet for introducing a rotating column of heated air to the casing to form a vortex, means forming a tapered slot in the casing, a scroll casing over the slot for directing heated air inwardly and off a tangent of the periphery of the casing therethrough into the casing, means in the casing forming a second tapered slot, a scroll casing over the second tapered slot for directing cold air inwardly and off a tangent of the periphery of the casing therethrough to the casing, means in the lower portion of the casing forming a downwardly converging outlet, and a scroll casing on the outlet having a deflecting surface on the bottom thereof converging upwardly into and centrally of the said last outlet for exhausting dried material without substantially disturbing the vortex, whereby the vortex may be maintained centrally in the casing throughout its entire length.

11. In a drying apparatus for removing moisture from atomized particles, the combination of a casing, means forming a plurality of tapered slots in and extending substantially around the periphery of the casing, and scroll casings over the said tapered slots for introducing air inwardly and off a tangent of the periphery of the casing into the casing.

12. In a drying apparatus for removing moisture from atomized particles, the combination of a casing having a lower portion converging to an outlet, means to supply air to the casing to form a vortex, scroll means for exhausting air and dried material outwardly from the casing, and deflecting means cooperating with the said outlet to maintain the characteristic flow, directing the suspended dried material to the said scroll means without substantially disturbing the vortex therein.

13. In a drying apparatus for removing moisture from atomized particles, the combination of a casing having a lower portion converging to an outlet, means to supply air to the casing to form a vortex, scroll means coaxially disposed about the casing, the said outlet extending downwardly into the said scroll means and centrally thereof to cooperate with the said scroll means in exhausting air and dried material outwardly from the casing without disturbing the vortex therein.

WILLIAM SPENCER BOWEN.
